[57] CLAIM

The ornamental design for a yard ornament, as shown and described.

DESCRIPTION

FIG. 1 is a perspective view of a yard ornament showing my new design therefor. The broken line drawing depicting an additional dalmatian and ribbon linking dalmatians to sled is for purposes of illustration only and forms no part of my design;

FIG. 2 is a top plan view;

FIG. 3 is a bottom plan view;

FIG. 4 is a left side elevational view;

FIG. 5 is a right side elevational view;

FIG. 6 is a front elevational view; and,

FIG. 7 is a rear elevational view.
